Geo. P. Kimmel. ATTORNEY.

UNITED STATES PATENT OFFICE.

WALTER R. GREGG, OF ST. LOUIS, MISSOURI.

WINDOW-SASH FASTENER.

Application filed November 7, 1925. Serial No. 67,607.

This invention relates to a window sash fastener, and has for its object to provide, in a manner as hereinafter set forth, a fastener of such class having means whereby the upper and lower sashes can be fastened in closed position, as well as in partially open position, relatively to each other, to allow for ventilation when desired.

Further objects of the invention are to provide, in a manner as hereinafter set forth, a window sash fastener which is simple in its construction and arrangement, strong, durable, thoroughly efficient and convenient in its use, readily installed and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a fragmentary view of a window frame and a pair of sashes and further showing in side elevation a sash fastener, in accordance with this invention, in locking engagement.

Figure 2 is a like view with the fastener in released position.

Figure 3 is a section on line 3—3, Figure 1.

Figure 4 is a section on line 4—4, Figure 3.

Figure 5 is a section on line 5—5, Figure 4.

Referring to the drawings in detail, 1 denotes the front, 2 the back and 3 one side of a window casing or frame, and 4, 5 and 6 the beads of the frame and between which the upper sash 7 and lower sash 8 slide. The lower rail 9 of the sash 7 has its rear side bevelled, as at 10, and the upper rail 11 of the sash 8 has its forward side bevelled, as at 12, whereby when the sashes are in closed position, the rails 9 and 11 will abut in the manner as shown to form a tight joint.

One of the side rails, as indicated at 13, of the upper sash is formed directly above the rail 9, with a vertically extending groove 14 in the rear face thereof, and the

rail 11 has its forward face, at one end, formed with a vertical groove 15. Secured in the groove 14, by the hold-fast devices 16, is a toothed bar 17, which provides what may be termed a ratchet strip.

Seated on the rail 11, at one end thereof, is a vertically disposed supporting member consisting of a base 18 formed with a pair of oppositely extending laterally disposed apertured flanges 19. Integral with the base 18 is a pair of spaced vertically disposed opposed arms 20, 21, each having an opening 22 near its upper end centrally thereof. Depending from the base 18 and the inner portion of each of said flanges is a rectangular extension 23, formed with an opening 24. The upper face of the base 18, in proximity to its forward end is provided with a socket 25.

The base 18, is seated on the rail 11 and secured therewith by the hold-fast devices 26 extending through the flanges 19 and engaging in said rail. The extension 23 snugly fits the groove 15 and is secured to the rail 11 by the hold-fast device 27 extending through the opening 24 and engaging in said rail.

Secured in the openings 22 is a pin 28, upon which is pivotally mounted a locking lever 29 formed of a substantially elongated rear or handle portion 30, an intermediate portion 31 of greater width and of less length than the handle portion 30, and a segment shaped forward portion 32 having a toothed forward edge 33 to engage the toothed bar 17 to lock the sashes together.

The forward portion 32 is of a width less than the length of the portion 31, and of a length greater than the width of the portion 31 and of greater thickness than the portions 30 and 31. The portion 31, between its vertical center and rear end, is formed with an opening 34 for pivotally mounting the lever 29 on the pin 28. The lower edge of the lever 29, at the point of joinder between the portions 30 and 31 is provided with a socket 35, which is positioned rearwardly with respect to the socket 25. The socket 35 extends rearwardly at an upward inclination, and the socket 25 is vertically disposed.

Mounted in the socket 25 is the lower end of an upwardly extending and rearwardly curved coiled controlling spring 36, which has its upper end seated in the socket 35.

Pivottally connected to the arm 21, be-

low the pin 28 and in proximity to the rear edge of said arm is a spring controlled latching lever 37 for maintaining the locking lever in inoperative position or with the toothed end of the locking lever clear of the toothed bar 17. The lever 37 is of curved contour and has its forward end provided with an opening 38 for pivotally mounting it on a pin 39, which projects from the outer side of the arm 21 and is positioned below the pin 28 and in proximity to the rear edge of the arm 21. The forward end of the lower 37 has projecting therefrom a hook-shaped extension 40, which is of inverted V shape, and the free or forward arm of said extension 40 is connected, as at 41 to the upper end of a controlling spring 42 therefor, and said spring has its lower end anchored to one of the flanges 19. The rear end of the latching lever 37 is formed with an opening 43 for the purpose of connecting a pull member 44 therewith. The lever 37, between its vertical center and its forward end has projecting from its upper edge a vertically disposed hook 45, adapted to engage over a laterally extending stud 46, carried by the locking lever 29, for the purpose of maintaining the latter free of the toothed bar 17, in a manner as shown in Figure 2.

In the operation of the device, should it be desired to raise the lower sash or lower the upper sash, the handle portion 30 of the locking lever 29 is pulled downwardly until the hook 45 overlaps the stud 46, as shown in Figure 2, whereby the teeth 33 are moved out of engagement with the teeth of the bar 17, thus releasing the sashes. Should it be desired to fasten the sashes in any position required, the member 44 is pulled downwardly releasing the hook 45 from engagement with the stud 46 and the teeth 33 will automatically engage with the teeth of the bar 17, thus fastening the sashes owing to the action of the spring 36.

It is thought that the many advantages of a window sash fastener, in accordance with this invention, can be readily understood, and although the preferred embodiment of the invention is as illustrated and described, yet changes in the details of construction can be had which will fall within the scope of the invention as claimed.

What I claim is:—

1. A window sash fastener lock comprising a toothed bar adapted to be carried by an upper sash, a spring controlled locking lever adapted to be carried by the lower sash and provided with means engaging with said bar for locking the sashes from movement, and further having intermediate its ends a lateral projection and a spring controlled latching lever engageable with said locking lever for maintaining the latter clear of said bar.

2. A window sash fastener lock comprising a toothed bar adapted to be carried by an upper sash, a pivot, a spring controlled locking lever adapted to be carried by the lower sash, mounted on said pivot in proximity to its inner end and provided with means engaging with said bar for locking the sashes from movement, said lever provided at a point between said pivot and its outer end with a lateral projection, a spring controlled latching lever arranged below and engageable intermediate its ends with said projection on said locking lever for maintaining the latter clear of said bar, and a pull member connected to said latching lever for releasing it from engagement with the locking lever.

3. A window sash fastener comprising a toothed bar adapted to be secured to one of the sashes of a window, a vertically disposed supporting member adapted to be secured to the other of the sashes of the window, a spring controlled locking lever pivotally mounted in said support and provided with means engaging with said bar for locking the sashes from movement, said lever projecting outwardly from said member and provided between the latter and its outer end with a lateral projection, and a spring controlled latching lever pivotally supported from said member below the locking lever and provided intermediate its ends with upstanding means engaging with said projections on said locking lever for maintaining the latter clear of said bar.

4. A window sash fastener comprising a toothed bar adapted to be secured to one of the sashes of a window, a vertically disposed supporting member adapted to be secured to the other of the sashes of the window, a spring controlled locking lever pivotally mounted in said support and provided with means engaging with said bar for locking the sashes from movement, said locking lever projecting outwardly from said member, a spring controlled latching lever pivotally supported from said member below said locking lever and provided exteriorly of said member with upstanding means engaging with said locking lever exteriorly of said member for maintaining the latter clear of said bar, and a pull member connected to the latching lever for releasing it from engagement with the locking lever.

5. A window sash fastener comprising a toothed bar adapted to be secured to one of the sashes of a window, a vertically disposed supporting member adapted to be secured to the other of the sashes of the window, a lever pivotally mounted within said member and provided with means engaging with said bar for locking the sashes, said member provided with a socket, said lever provided with a socket rearwardly with respect to the socket in said member, and a

controlling spring having its upper end seated in the socket in the lever and its other end extended into the other of said sockets.

6. A window sash fastener comprising a toothed bar adapted to be secured to one of the sashes of a window, a vertically disposed supporting member adapted to be secured to the other of the sashes of the window, a lever pivotally mounted within said member and provided with means engaging with said bar for locking the sashes, said member provided with a socket, said lever provided with a socket rearwardly with respect to the socket in said member, a controlling spring having its upper end seated in the socket in the lever and its other end extended into the other of said sockets, and a spring controlled latching lever pivotally supported from said member and provided 20 with means engaging with the locking lever for maintaining the latter clear of said bar.
7. A window sash fastener comprising a toothed bar adapted to be secured to one of the sashes of a window, a vertically disposed supporting member adapted to be secured to the other of the sashes of the window, a lever pivotally mounted within said member and provided with means engaging

with said bar for locking the sashes, said member provided with a socket, said lever provided with a socket rearwardly with respect to the socket in said member, a controlling spring having its upper end seated in the socket in the lever and its other end extended into the other of said sockets, a 35 spring controlled latching lever pivotally supported from said member and provided with means engaging with the locking lever for maintaining the latter clear of said bar, and a pull member connected to the latching 40 lever for releasing it from the locking lever to free the latter.

8. A window sash fastener comprising a toothed bar adapted to be carried by an upper sash, a spring controlled locking lever 45 adapted to be carried by the lower sash and provided with means engaging with said bar for locking the sashes from movement, and a spring controlled locking lever engageable intermediate its ends with said locking lever 50 for detachably maintaining the latter clear of said bar.

In testimony whereof, I affix my signature hereto.

WALTER R. GREGG.
